UNITED STATES PATENT OFFICE.

PAUL BROWN KLUGH, OF CHICAGO, ILLINOIS, ASSIGNOR TO THE CABLE COMPANY, OF CHICAGO, ILLINOIS, A CORPORATION OF ILLINOIS.

BELLOWS-CHEST.

No. 914,351.

Specification of Letters Patent.

Patented March 2, 1909.

Original application filed November 18, 1905, Serial No. 287,989. Divided and this application filed January 7, 1908.
Serial No. 409,680.

To all whom it may concern:

Be it known that I, PAUL BROWN KLUGH, a citizen of the United States, residing at Chicago, in the county of Cook and State 5 of Illinois, have invented certain new and useful Improvements in Bellows-Chests, of which the following is a specification, reference being had therein to the accompanying drawings.

10 My invention relates to bellows chests for pneumatically operated piano players.

The object of the invention is to provide economical and efficient mechanism of this character, readily fitted and attached within 15 the case of an ordinary piano of standard size and as readily removed therefrom, adapted to be attached or removed in separate sections in building, repairing or gaining access to parts normally concealed by 20 the chest, without necessitating the removal or disturbance of the entire bellows chest and having capacity for maintaining substantially uniform tension throughout the several sections.

25 In general, the invention contemplates the construction of a bellows chest comprising a plurality of sections each separately attached and removable or detachable one from the other, two corresponding sections 30 being operated by the usual bellows or tension creating mechanism, and means for removably securing the sections in pneumatic intercommunication within a piano below the keys.

35 In the accompanying drawings I have shown a device embodying my invention in its preferred form.

Figure 1 is a front view of a piano showing the device in attached position below the 40 key-bed, and Fig. 2 is an enlarged broken cross-section on line 2 of Fig. 1, illustrating my preferred method of attaching the sections within the piano the pumps and reservoirs omitted.

45 In the drawings, I have shown a bellows chest composed of two sections *a* *a'*, but it is obvious that any plurality may be used, where desired. Two corresponding sections are each provided with the usual pumping 50 bellows *8* *8'*, expandible reservoirs *10* *10'*, pedal mechanism, ports and valves for maintaining pneumatic tension within the sections. These tension-creating devices being well known in the art, need not be further

described. The sectional construction of the 55 bellows chest enables the builder to separately distribute the several sections and makes it possible to fit the chest into piano cases of different widths and facilitates attachment and detachment. In order to gain 60 access to the bottom of the string frame *Q* without disturbing any of the sections, an operation which is frequently desirable in supplying new strings, it will be found convenient to recess the sections at 15 to provide 65 the necessary opening. In order to secure the outer ends of the right and left hand sections, or those adjacent to the inside of the end walls of the piano, I prefer to secure a pair of upright cleats 5 and 5^a on 70 the left hand end and 6 and 6^a on the right hand end, both pairs tapering inwardly so as to form the oppositely disposed recesses or sockets. Cleats on the same side of the case of the piano are far enough apart to 75 permit the outer ends of the exhaust device to fit snugly between them. Adjacent ends of sections I prefer to secure or interlock by providing upright supports 1, having two vertically disposed straps countersunk 80 and bent over the top at right angles, so that they may be screwed, or otherwise removably secured, to the piano, either to the key-bed or to the lower end of the string frame *Q*. 85

Rigidly secured to each upright 1, or made integral with it, is a vertical wedge block or tongue 4, tapering outwardly and of sufficient size to fill the intervening space between adjacent ends of the sections when in place. The end sections are secured within the instrument by thrusting the outer ends of each into the sockets between the cleats 5 5^a and 6 6^a and pressing the inner ends against the wedge member 4 and securing 95 the upright support 1, as above described. The relative size of the parts is such that the tapering sides of wedge 4 when used between the adjacent ends of sections crowd and hold them together, in which position they may 100 be detachably fastened by suitable bolts and nuts 3 and 3^a passing through upright 1.

In order that the pneumatic tension may be the same within the sections, I cut an opening in each and fit the end of a detachable and flexible pipe or other wind-way connection thereto, indicated in the drawings by 12. The configuration of the ends

of the sections I prefer to form so that ready access may be had to the string frame Q through the opening 15.

I am aware that many modifications in the construction and method of securing the sections will suggest themselves to those skilled in the art, and I do not wish to be understood as limiting myself to the device described and shown; but

10. What I claim is—

1. In a piano player, in combination with a piano having sockets disposed on opposite sides thereof beneath the keys, a bellows chest composed of a plurality of sections, the ends of said sections adjacent to said sockets being adapted to fit therein, and vertical wedge blocks adapted to fit between adjacent inner ends of said sections, whereby said sections are separately removably secured within the piano.
15. 2. In a piano player, in combination with a piano having sockets disposed on opposite sides thereof beneath the keys thereof, a bellows chest, the ends thereof adjacent to said

sockets being adapted to fit therein, whereby 25 said chest is removably secured within the piano.

3. The combination of bellows chest sections, oppositely disposed sockets secured on the sides of the interior of a piano below the 30 keys and wedge tongues adapted to be inserted between the inner ends of said sections to force said outer ends into said sockets, whereby said sections are locked to the piano, substantially as described. 35

4. The combination of the bellows chest sections a a' , a pipe connecting them, oppositely disposed sockets adapted to be secured on the sides of a piano, and a wedge member adapted to hold the ends of said sections 40 in said sockets and to be locked to the piano, substantially as described.

In testimony whereof I hereunto affix my signature in the presence of two witnesses.

PAUL BROWN KLUGH.
